MEANS FOR TUNING RADIO RECEIVING APPARATUS

Carl Kohlsaat, Brookfield, Ill., assignor of one-half to Floyd E. Foster, Brookfield, Ill.

Application January 13, 1933, Serial No. 651,466

15 Claims. (Cl. 250—20)

This invention relates to means for tuning radio receiving apparatus, and has for its general object to improve and simplify, in a practical and efficient manner, the selection and tuning in of desired broadcasts for automatic reception, as well as for the manually operative selection of various broadcasts individually, at will.

One of the principal objects, more specifically stated, is to provide a time controlled mechanism, embodying a combination of mechanical and electrical operating and controlling elements or devices, which may be installed in connection with an ordinary radio receiving set without necessitating any material alteration in the original receiving set or the applied station selecting means.

A further object is to provide for the automatic rendition of selected programs at predetermined intervals after a pre-setting of the manually operable station selecting element, and also the automatic cessation of the reception at a predetermined time.

Other objects and advantages to be attained will hereinafter more fully appear.

The invention consists in the general construction and arrangement of the apparatus, and in the parts and combinations and arrangements of parts as hereinafter described and pointed out with particularity in the appended claims.

In the accompanying drawings, illustrative of a practical adaptation of the invention, and forming a part of the present specification.—

Fig. 1 is a front elevation of the cabinet or housing of a radio receiving set, showing the exposed parts entering into the control and operation of the apparatus;

Fig. 2 is a view, partly in rear elevation, with certain parts broken away and shown in section, and other parts more or less in diagram;

Fig. 3 is a similar view, with parts of the radio receiving apparatus removed from the cabinet or housing;

Fig. 4 is a horizontal section through the lower portion of the cabinet or housing, taken on or about the lines 4—4 of Figs. 1 and 2, and illustrating in plan view the parts therein contained;

Fig. 5 is a vertical section, taken on or about the lines 5—5 of Figs. 1 and 2;

Fig. 6 is a detail view, in side elevation, with parts broken away, of one of the rotary discs of the automatic station selecting and controlling means;

Fig. 7 is a detail view of one of the disc spacing collars or washers;

Fig. 8 is a fragmentary detached view, on an

enlarged scale, taken substantially on the line 8—8 of Fig. 1, and showing the working relation of the battery of rotary discs of the automatic station selecting and controlling means in plan view in connection with the regular station indicating dial of the receiving set and the directly associated operating means, and the correlated time selecting scale on the outer side of the cabinet or housing being shown in face view diagrammatically in connection with the holes for the removable key pin used in the setting of the rotary disc elements;

Figs. 9, 10, and 11 are sectional views, taken respectively on the lines 9—9, 10—10, and 11—11 of Fig. 8, as illustrative of relative positioning of the rotary disc elements for different timing of reception;

Fig. 12 is a fragmentary detail sectional view, on an enlarged scale, taken on or about the lines 12—12 of Figs. 2 and 3, to show the working relation of the terminal time controlling elements and the rotating brush contact members carried by the clock mechanism; and

Fig. 13 is a general wiring diagram of a complete assembly of the working adaptation of the invention as illustrated in the preceding figures of the drawings.

Referring now to the drawings, the numeral 20 designates the cabinet or housing of an ordinary radio receiving apparatus which will be described herewith in a practical adaptation of the invention. As shown, the front wall or panel 21 of the cabinet is provided with a vertically elongated slotted opening 22 through which slightly protrudes a peripherally toothed wheel 23 which may be rotated by manual manipulation and is in mesh with a gear 24 secured on a shaft 25 carrying the rotary dial wheel 26, which latter has the broadcasting station numbers or wave lengths of the respective stations indicated peripherally thereon, as at 27, and exposed through the sight opening 28 provided therefor in the front wall of the panel of the cabinet. In the particular radio receiving apparatus of the illustrative adaptation of the present invention, said shaft 25 also carries the rotors 29 which cooperate with the stationary stators 30 of the regular condensers of the apparatus, of which there are two illustrated, as at 31 and 32.

On the outer side of the front panel or wall 21 of the cabinet, and adjacent the sight opening 28, as shown, is a knob 33 which is fixed on the operating shaft 34 of a combined "off" and "on" switch and volume regulator 35 located on the inside of the cabinet adjacent the front wall 25.

or panel 21. By turning the knob 33 to its "off" position the switch of the controlling element 35 is opened and the electrical circuit through which the current is supplied to energize the several 5 tubes and other electrical interior appliances within the chassis or body of the receiving set is broken, whereas if the knob 33 is turned in the opposite direction, to the "on" position, said electrical circuit is, of course, closed and the parts of 10 the radio set connected therein are either energized or in operable condition; that is to say, the several tube elements are energized and all other electrically operated or controlled parts have their respective connections or actuating elements 15 in energized or operable condition. In other words, the receiving apparatus is in receiving condition except as to the selection of the particular station to be tuned in, which, of course, is effected by adjustment of the condensers 31 20 and 32 through the manipulating means hereinbefore described for the manual tuning in operation.

It may be here stated that the receiving apparatus, which, as hereinbefore specified, may be of 25 any ordinary construction and arrangement and, of itself, forms no part of the present invention except as to the cooperative connection of the operating and controlling means of the present invention therewith, may have all of the component parts, including the sound amplifier, or "loud speaker," enclosed within a single cabinet or housing of the regular small portable type or larger and more elaborate console or other style 30 of furniture, as may be desired. In the apparatus illustrated in the accompanying drawings, the cabinet or housing contains only the chassis or main body portion of the receiver and associated parts of the present invention, and the loud speaker (not shown) may be located in any convenient place, either relatively near or remote 35 from the cabinet, and connected through its extension cord by plugging into a socket 36 in one of the side walls 37 of the cabinet. So, too, a socket 38 may be conveniently located in the opposite side wall 39 of the cabinet for the plugging in of a cord as usually employed for effecting the connection with the source of electrical supply, said plug being indicated at 40 in Fig. 2 of the drawings and detached from said socket 38. 40

The socket and plug elements 38 and 40 may have any suitable interfitting provisions, but, as shown, the plug is provided with terminal pins 41 and 42, which are respectively connected to the circuit supply wires 43 and 44, and being insertable into openings in socket terminal elements (not shown), said socket terminal elements having circuit wires 45 and 46 connected thereto, and the wires 45 and 46 being respectively connected to terminal contacts 47 and 48 of a junction block 49 secured on the inner side of the wall 39 of the cabinet adjacent to said socket element 38, as shown structurally in Fig. 2, but more clearly shown diagrammatically in Fig. 13. This junction element 49 may be in the form of the ordinary commercial block type in which bus bars or electrical conductor elements 50 are embedded in a body of insulating material such as that commercially known as "bakelite" or the like or any other suitable structure of the box-like type commonly used for the purpose. As shown, the junction block 49 has a third terminal contact 51 in line with the hereinbefore mentioned terminal contacts 47 and 48, said contacts 47, 48, and 51 55 being respectively connected by the embedded bus

bars 50 to an upper row of terminal contacts 52, 53, and 54.

As shown more clearly in Fig. 13 of the drawings, a circuit wire 55 leads from the lower terminal contact 47 into the radio receiver chassis, 5 designated, as a whole, by the numeral 56. From the receiver chassis 56 a return wire 57 leads to and is connected with the lower terminal contact 51 of the junction block 49.

As thus far described, it is obvious that electrical current from the source of supply, through the plug 40 when attached in the socket element 38, will pass through the wire 55 into the radio receiver and thence out through the wire 57 to said terminal contact 51 and then through the bus 15 bar or conductor 50 to the correlated upper terminal contact 54 which is in turn connected by a wire 58 to a switch terminal 59. Adjacent said switch terminal 59 is a companion terminal 60 which is connected by a wire 61 to the middle upper terminal contact 53 of the junction block 49, the circuit being completed through the connecting bus bar or conductor element 50 and correlated middle lower terminal contact 48 and return wire 46 to the socket element 38 and the return wire 44 leading from the attached plug 40 to the source of electrical energy; that is to say, the circuit just described is completed when the switch terminals 59 and 60 are cross-connected by a switch element 62, which functions 30 in the control and operation of the automatically operable parts of the apparatus, as will later be more fully set forth.

As just above stated, the circuit for the source of supply of electrical energy to the chassis 56 of the receiving set is completed when the switch element 62 is in position to connect the two terminal contacts 59 and 60 but, provided, of course, the switch portion of the combined switch and volume regulator 35 is in closed or "on" position, 40 to which position it is preliminarily moved to place the radio receiver in condition to be operated and controlled either manually or automatically, as will hereinafter more clearly appear. In this connection, it may be here stated that the combined switch and volume regulator 35, which is connected to the receiver chassis 56 in the ordinary and obviously well known manner, is merely shown conventionally and is connected to the chassis and framework for completion of the circuits and requisite grounding by the wires 63, 64, 65, and 66, respectively. 50

The apparatus thus far described is operable manually for the tuning in of the desired stations in the ordinary way. The mechanical and electrical controlling and operating parts of the present invention will now be described. Generally stated, the invention comprises a clock mechanism, a station selecting and timing unit correlated to the clock mechanism and the hereinbefore described manually operable dialing and controlling mechanism, and a cooperating automatically controlled motor.

The clock mechanism, as shown, includes an ordinary electrical clock mounted in a circular housing 67, said housing being secured on the inner side of a supplemental panel plate 68, of insulating material, secured in an opening provided therefor in the front wall or panel 21. In the supplemental panel plate 68 is a central opening through which the dial 69 of the clock is exposed. Surrounding the clock dial 69, on the outer face of the dial plate 68, is an annular supplemental dial 70 marked with twelve equally 75

spaced radial lines 71 corresponding to the hour marks of the clock dial proper. Midway between each of the radial lines 71 is a relatively shorter line 72, said lines 72 indicating half hours, while the spaces between the lines 71 and 72 are again equally divided by still shorter lines 73 indicative of quarter hours.

Preferably, the lines 71 are numbered from 1 to 12, inclusive, in correlation to the corresponding numbers on the clock dial proper, to facilitate the utilization of an annular series of open-ended socket tubes 74 surrounding said supplemental dial 70, there being forty-eight of these tubular socket members 74 correlated one each to the several radial lines 71, 72, and 73 of said dial 70. These open-ended socket tubes 74 are composed of metal, preferably copper on account of its electrical conductivity, and said tubes project some distance beyond the inner face of said supplemental panel plate 68, which, as hereinbefore stated, is preferably of material of non-electric conductivity, and thus the tubular members 74 are insulated from each other.

Each of the tubular socket members 74 is connected individually by a wire 75 to a brush element 76, of which there are, of course, forty-eight, in accordance with the structure herein illustrated, and, in any case, a number corresponding to the number of socket tubes 74 employed. As shown, the several brush elements 76 are mounted on a supporting bar 77 and insulated from each other, preferably in a simple manner by making the bar 77 of suitable insulating material. As shown structurally in Figs. 2 and 3, and diagrammatically in Fig. 13, said wires 75 are gathered into an annular cable structure or protective covering 78 and distributed at their opposite ends from said cable structure or covering to the respective socket tubes 74 and brush elements 76.

Each of the brush elements 76 has a slidable engagement at its free end with a circular disc element 79 which is mounted loosely on a shaft 80 but is normally frictionally held, as will be presently described, so as to rotate with the shaft unless positively held from rotation, or has applied thereto braking resistance overcoming the frictional clutch connection between it and said shaft 80. In the illustrative structural adaptation of the present invention, said shaft has the hereinbefore mentioned peripherally toothed wheel 23 secured directly thereto whereby the one rotates in fixed relation to the other, and by which connection with the wheel 23 and the gear 24, as hereinbefore described, the dial wheel 26 and rotors 29 of the condensers 31 and 32 of the radio receiver are simultaneously rotated in correlation to the discs 79, of which latter there are forty-eight, corresponding to the number of brushes 76 and socket tubes 74 in the structure shown.

Interposed between each of the discs 79 is a washer 81 in the central opening of which is a key lug or projection 81' which slidably fits a longitudinal slot 82 in the shaft 80 whereby to be freely adjustable endwise of the shaft but fixed to rotate positively therewith. At one end of the shaft 80 is a collar 83 which abuts a supporting bracket 84 projecting from a metal lining plate 85 secured on the inner face of the front wall or panel 21 of the cabinet. The next adjacent endmost disc 79 on the shaft 80 abuts said collar 83 and the intermediate discs 79 and washers 81 are clamped in frictional engagement between said

endmost disc abutting the collar 83 and the opposite endmost disc against the outer face of which a loose collar 86 abuts, said collar 86 being pressed by a spring element 87 interposed between said collar 86 and another collar 88 abutting a supporting bracket 89. It may be here also noted that the supporting bar 77 for the brush elements 76 is conveniently mounted on said supporting brackets 84 and 89.

Each of the disc elements 79, which are made of metal of electrical conductivity, preferably brass, has a peripheral aperture or recess 90 and a diametrically disposed circumferential insert 91 of insulation material, so that when its cooperating brush element 76 is in contact therewith at any point throughout its circumference except where the non-electrical conductive insert 91 is located, current is conducted through the brush element and the engaged disc member 79 and the metallic supporting frame including the bracket 20 elements 84 and 89 and the lining plate 85, which latter is electrically connected by a wire 92 to a solenoid magnet coil 93, from which latter a wire 94 leads to the terminal 95 of a switch element 96, whose opposite terminal 97 is connected by a wire 98, as at 99, to a switch terminal 100. Said wire 98 is also connected, as at 101, with a solenoid magnet coil 102, from which latter leads a wire 103 which is extended through an aperture 104 in the front wall or panel 21 of the cabinet and is provided at its outer end with a plugging-in pin 105 for insertion in one of the tubular socket members 74 for the purpose of functioning as a circuit terminal contact in automatically stopping operation of the receiver at a predetermined time, said pin being hereinafter identified and referred to as the "stopping" pin.

A second plugging-in pin 106, identical in form and size with the pin 105, and applied in the same way, except for a different purpose, namely, that of starting instead of stopping automatic reception, and hereinafter identified and referred to as the "starting" pin, is provided at the outer end of a wire 107 extended outwardly through an opening 104a in the front wall or panel 21 of the cabinet, similar to the opening 104 for the wire 103, said wire 107 being connected on the inside of the cabinet to a solenoid magnet coil 108 whose opposite circuit wire 109 is connected to a switch terminal contact 110.

Associated with the switch terminal contact 100 is a companion terminal contact 111, said terminal contacts 100 and 111 being connectible by a switch element 112 which is operably connected to the reciprocating core element of the solenoid 102 by an insulated cross-head 113 which also carries the attached switch element 62, whereby said switch elements 62 and 112 are simultaneously actuated in closing and breaking the connections between said switch terminal contacts 59, 60, and 100, 111. The switch terminal contact 110 has associated therewith a companion terminal contact 114, said terminal contacts 110 and 114 being connectible by a switch element 115 which is attached by an insulated arm 116 to the reciprocating core member of the solenoid 108, whereby when the core member is moved in one direction the switch element 115 is moved to close the circuit across the contacts 110, 114, and in the opposite direction the circuit is broken. In the diagram illustrated in Fig. 13 of the drawings, the switch element 62 is shown in connecting relation to the terminal contacts 59 and 60, and likewise the switch element 112 with the 75

terminal contacts 100 and 111, while the switch element 115 is moved out of connecting relation to the terminal contacts 110 and 114. At this time, as illustrated in the diagram, neither the 5 stopping pin 105 nor the starting pin 106 is plugged in or inserted in any one of the tubular socket members 74, but their functioning effect will hereinafter be described. However, at this 10 time, the receiving set is in operable condition and under the control of a clock mechanism, to be later more fully described.

As shown, the two switch terminal elements 111 and 114 are connected by a wire 117 which is in turn connected by a wire 118 to the secondary coil 119 of an adjustable transformer 120, the opposite circuit wire 121 of said secondary coil 119 being connected electrically with the clock housing 67 through a connecting bar or plate 122 and the supporting bracket member 123.

20 The primary coil 124 of the transformer 120 is connected at one end by a wire 125 to the terminal contact 47 of the junction block 49, which is connected through the wire 45, socket 38, and plug terminal pin 41 to the lead-in wire 43 from the source of electrical supply (not shown). From the opposite end of the primary coil 124 a wire 126 leads to the terminal contact 48 of the junction block 49.

From the terminal contact 53, which is connected by the bus bar or conductor element 50 to said terminal contact element 48, a wire 127 leads and is connected to a wire 128, which in turn is connected to the internal motive mechanism (not shown) within the clock housing 67. 35 The circuit from the clock operating mechanism is completed through a wire 129 which is connected to a wire 130 leading and connected to the terminal contact 52 of the junction block 49.

The circuit wire 127 beyond the junction with 40 the clock wire 128 is connected to an electric motor 131, from which, in turn, a wire 132 leads to a switch terminal contact 133. Associated with said switch terminal contact 133 is a companion terminal contact 134 to which the wire 45 130 is extended from the junction of the clock wire 129 and there connected. These terminal contacts 133 and 134 are connectible by a switch element 135 which is normally out of engagement with said terminal contacts but is brought 50 into circuit closing engagement by the energization of the solenoid magnet 93.

Adjacent the companion switch terminal contacts 133, 134, is a pair of terminal contacts 136, 137, which are normally cross-connected by a 55 switch element 138 having an operative connection with the reciprocating core of the solenoid 93 whereby, upon the energization of the solenoid coil, the switch element 138 is moved out of engagement with said terminal contacts 136 and 137 simultaneously with the movement of the 60 opposed switch element 135 into circuit closing engagement with said terminal contacts 133, 134. The terminal switch contact 137 is connected, by a wire 139, into one of the circuits of the sound 65 amplifier and loud speaker circuits of the receiving set within the chassis 56, while from the terminal contact 136, when the switch element 138 is in circuit closing engagement with said 70 contacts 133 and 137, a wire 140 leads and is connected to the terminal portion 141 of the plugging-in socket member 36 at the place where one of the connections is made with the tone transmitting portion of the loud speaker. From 75 the opposite terminal 142 a wire 143 leads back

into the chassis 56, thereby completing the circuit. From the other terminals 144 and 145 of the plugging-in socket 36, wires 146 and 147, respectively, lead into the chassis 56 to complete the other circuit of the sound amplifier and loud speaker.

It may be here noted that during the time the motor 131 is in operation and performing the function for which it is especially provided, as will be presently more fully explained, it is desirable to have the loud speaker cut out, and it is for this reason that the provision is made for breaking the circuit connection between the terminal contacts 136 and 137 when the motor circuit is closed by the operation of the solenoid 93 15 and the resultant engagement of the switch element 135 with the terminal contact members 133 and 134. In other respects the circuit arrangements are the same as provided in the ordinary radio receiving apparatus. 20

Before entering into a more complete description of the function of the hereinbefore mentioned disc members 79 and their manner of selective adjustment, and also their eventual operation, into which the electric motor 131 enters, the device for 25 effecting electrical contact and circuit connections with and between the inner end portions of the tubular socket members 74 and the clock body frame or housing 67, and likewise between the inner end portions of the inserted stopping pin 105 30 and starting pin 106 and said clock frame or housing 67, will be described. For this purpose a rotary element 148 is located between the supplemental panel plate 68 and the clock housing 67 35 which is supported in spaced relation to said panel plate by the supporting bracket members 123, of which there are four diagonally disposed, as best shown in Figs. 2 and 3, said diagonal members being supported at their outer ends by plates 149, which latter are secured to the inner face of the 40 front wall or panel 21. In this connection, it may be also noted that the clock dial proper 69 is mounted in a circular opening provided therefor in the supplemental panel plate 68. Therefore the space between the supplemental panel 68 and 45 the clock housing 67 is provided for the accommodation and operation of the rotary element 148 which, although not shown in detail, is obviously mounted in any suitable manner to rotate with the hour hand of the clock, but preferably by direct attachment to the spindle of the clock mechanism which ordinarily carries the hour hand, by which mounting and operation said rotary element 148 makes one complete revolution every 50 twelve hours. 55

The rotary element 148 may obviously be in the form of a radial arm, as shown. At the outer end thereof there is formed integrally or otherwise provided a resilient contact member 150 which is slotted longitudinally inward from its outer end 60 to provide a pair of separate tongue portions 151 and 152. The tongue 151 next adjacent the panel plate 68 travels in a circular path into which the inner ends of the tubular members 74 project, while the inner tongue 152 travels in a circular 65 path into which the inner end portion of the inserted starting pin 106 of the stopping pin 105, as the case may be, projects, as shown more clearly in Fig. 12 of the drawings. It will thus be seen that whenever the tongue portion 151 engages any of the socket members 74 or the tongue portion 152 engages the inserted pin 105 or 106, as the case may be, an electrical circuit may be completed through the rotary member 148 and the 70 75

hour hand shaft of the clock mechanism, and through the housing 67 thereof, and supporting bracket member 123 and the connecting plate 122 to the wire 121 and secondary coil 119 of the transformer 120, as hereinbefore described.

The shaft 80 on which the circular disc elements 79 are mounted has a circumferentially grooved clutch disc 153 feather-keyed thereon, as at 154 (see Figs. 3 and 8), said clutch disc being engaged by the upper yoke portion 155 of a shifter lever 156 which is pivoted, as at 157, to a bracket member 158 secured on the inner lining plate 85. Connected to the lower end of the shifter lever 156 is a spring 159 which functions to move the lever 156 and yieldably hold the clutch disc 153 in engagement with a notched hub portion 160 of an oscillatory crank arm 161 which is sleeved loosely so as to rotate freely about the shaft 80, on the end of which it is mounted, except when engaged by the clutch member 153 which locks it to the shaft 80 against rotation independently thereof.

In order to hold the clutch collar 153 out of engagement with the hub portion of the crank arm 161 when it is desired or necessary to permit rotation of the shaft 80 in making adjustments of the discs 79 thereon without effecting movement of the crank arm 161, a crank arm 162 is mounted on a shaft 163 projected through the front wall or panel 21 of the cabinet and provided at its outer end with a knob 164 by which the shaft 163 may be turned to oscillate the crank arm 162. On the crank arm 162 is a pin 165 which engages the lower end portion of the shifter lever 156 when the shaft 163 is turned in one direction, whereby to move the clutch collar 153 from engagement with the hub portion 160 of said arm 161.

The crank arm 161 is connected by a link 166 to a rotating crank arm 167 which is attached, integrally or otherwise, to the hub portion 160 of a worm gear wheel 169, or directly to the shaft 170 on which said worm gear 169 is fixed, so as to rotate therewith. The shaft 170 is journaled in the bearing portion 171 of a supporting bracket 172 which is attached to a block member 173 secured on the under side of the top wall 174 of the cabinet, there being preferably a plate of insulating material 175 interposed between the bracket 172 and the block 173. Journaled in bearings 176, provided therefor on the bracket member 172, is a worm screw 177 which meshes with the gear 169, the shaft portion 178 of said worm screw 177 being provided with a spur gear 179 which is in mesh with a pinion 180 on the power shaft 181 of the hereinbefore mentioned electric motor 131, the operation of which latter is automatically started and stopped, as will be later more fully described.

Before describing the automatic stopping and starting of the electric motor 131 it may be here stated that in order to place the radio receiver in receptive condition the on-and-off switch 35 must be closed, and, further, the switch elements 62 and 112 must also be in circuit closing relation to their respective terminal contacts 59, 60, and 100, 111, which latter have been previously described herein more particularly with reference to the diagram illustrated in Fig. 13, and as to their operation automatically by the completion of electrical circuits through the insertion of the stopping pin 105 and starting pin 106, but said elements, together with their respective cooperative solenoids 102 and 108, are illustrated mechanically in Figs. 2 and 3 of the drawings and are manually operable, as will now be set forth.

In the mechanical structure illustrated, said

switch elements 62 and 112, and also the hereinbefore described switch element 115, are operably connected to a common actuating shaft 182 of insulating material which is provided with a lever arm 183 having an operable connection with an intermediate neck portion 184 connecting the core members of the two solenoids 102 and 108, said lever arm 183 being rocked in opposite directions upon the alternate energization of the solenoids 102 and 108, and the shaft 182 on which the arm 183 is mounted being also extended through the front wall or panel 21 of the cabinet and provided on its outer end with a knob 185 by which the shaft may be turned manually to effect the opening and closing of the circuits which are automatically opened and closed by the operation of the solenoids 102 and 108. Thus to start or stop the operation of the radio receiver, said knob 185 may be accordingly manipulated manually.

Each of the disc members 79 is effectively correlated to a given period of time for the automatic operation of the radio receiver. That is to say, for example, the clock controlling and operating mechanism is divided into forty-eight periods, of fifteen minutes each, and, accordingly, there are forty-eight of the disc members 79 in the practical adaptation of the invention illustrated. In other words, the several tubular socket members 74 are spaced in the annular series at radial points corresponding to the quarter-hour divisions of the clock dial proper 59, and each of the socket members 74 has one of the disc members 79 correlated thereto and operably connectible electrically by its circuit wire 75 and brush element 76; and when it is desired to receive the broadcast from any particular station, and during a given fifteen-minute or quarter-hour period, the disc for that period is adjusted with respect to the station selecting dial wheel 26. To accomplish this a setting pin 186 is insertable in any one of a series of apertures 187 provided in the front wall or panel 21 of the cabinet in a horizontal row, and each of the holes being correlated to one of said discs 79 so that when the aperture or recess 90 of the disc is brought into registering alignment with its correlated pin receiving hole 187, the inserted setting pin will enter the aperture or recess 90 of the disc 79 and hold the disc against rotation.

Prior to adjustment, of course, the clutch 153 must necessarily be thrown out of engagement with the hub portion 160 of the crank arm 161 so that shaft 80 is free to be rotated manually by the manipulation of the toothed wheel 23 which is projected through the opening 22 in the front wall or panel 21.

It will be here noted that when the particular disc 79 is held against rotation by the inserted key or setting pin 186, all of the other disc members 79 rotate with the shaft, owing to the frictional engagement of said disc members with the spacing washers 81 which are feather-keyed to the shaft. At the same time, owing to the intermeshing of the toothed wheel 23 with the gear 24 on the shaft 25, the dial wheel 26 carrying the broadcasting station identification symbols or call numbers 27 is rotated with the shaft 80; and when the identification symbol or number for the particular broadcasting station to be selected appears at the middle of the sight opening 28 in the front wall or panel 21 the operator ceases manipulation of the wheel 23 and withdraws the key or setting pin 186 from engagement with the disc 79 and entirely from the hole 187 in the front wall or panel 21. When the key or setting pin 186 is

not in use it may be inserted in a dead hole in the front wall or panel, as shown at 188 in Figs. 1 and 8 of the drawings.

Preferably, a scale plate 189 is provided on the outer face of the front wall or panel 21 with holes 193 registering with the key or setting pin holes 187 in the front wall or panel proper 21, and, also, the holes 187 register with a corresponding series of holes 191 in the lining plate 85. As shown more clearly in Figs. 1 and 8 of the drawings, the scale plate 189 is provided with twelve relatively long division lines 192, corresponding to the relatively long radial lines 71 of the annular supplemental dial 70, and respectively correlated to the apertures 190 for the setting of the discs 79 on the hour, these particularly correlated holes being respectively numbered from 1 to 12, inclusive, as are the lines 71 of said annular dial 70. The intermediate holes for the setting of the discs 79 on the half-hour have correlated therewith relatively shorter lines 193 on the dial plate 189, similar to the radial lines 72 of said annular dial 70, while the holes 190 for the setting of the discs 79 on the quarter-hour have correlated short lines 194, said lines obviously facilitating the application of the key or setting pin 186 in the proper hole in the dial plate 189 for the disc setting for reception of the desired program at a definite time.

It may be here stated, when a disc element 79 is engaged by the key or setting pin 186 the insulated or dead spot 91 of the disc is engaged by its correlated brush element 76 and, while the disc element 79 is so held, the dial wheel 26 is rotated to bring into register with the center of the sight opening 28 the identification symbol or number of the particular station whose broadcast it is desired to receive at the time for which the disc element 79 is set, after which the key or setting pin 186 is removed from engagement with said disc 79, and the disc thereafter moves in the same set relation to the dial wheel 26 until it is readjusted relative thereto for some other station. This is true because the disc shaft 80 and the shaft 25 carrying the dial wheel 26 and condenser rotors 29 of the radio receiver are never turned in either direction one full revolution, but, on the contrary, are merely oscillated back and forth, either when manipulated manually in the setting operations or under the driving power of the motor 131, as presently described. This limitation to oscillatory movement is because of the fact that the condenser rotors 29 are limited in their rotative movement so that the shaft 25 only turns through a range of approximately 180 degrees; and the shaft 30, owing to its gear connection with the shaft 25, oscillates through approximately the same range, or even to a lesser degree, and also due to the relative lengths of the crank arms 161 and 167, the crank arm 161 being somewhat longer than the arm 167 so that it merely oscillates while said crank 167 is making a complete revolution with the worm gear wheel 169.

In order to operate the radio receiver either by the selection of the desired broadcasting station by manual manipulation only, or by the utilization of the automatic operating and controlling elements, the on-and-off switch 35, as hereinbefore set forth, must be turned on, either before or after the manual station selecting adjustment has been made. So, too, whether the radio receiver is to be operated only by manual manipulation and control or by the use of the automatic controlling and operating elements,

the switch knob 185 must be turned to "on" position to close the switches 62 and 112, as hereinbefore specified, except in cases where it is desired to set the disc members 79 at a considerable time before the broadcast is to be received automatically, and then said knob 185 may be left in the "off" position, with said switches 62 and 112 correspondingly in opened position to be closed by the insertion of the starting pin 106 in the tubular socket member 74 at the time corresponding to the time in which it is desired to automatically start the reception of the selected broadcast, in which latter position of the knob 185, the switch 115 is in closed position whereby the circuit for the solenoid 108 is closed until such time that the tongue portion 152 of the contact member 150 moves into engagement with the inserted starting pin 106.

When the tongue portion 152 of the rotating contact member 150 engages the inserted starting pin 106 the circuit is completed through the arm 148 which carries said contact member 150, the clock frame and housing 67, supporting bracket 123, connecting bar 122, wire 121, secondary coil 119 of the transformer 120, wires 118 and 117, contacts 114 and 110 which are closed at the time by the switch element 115, wire 109, coil of the solenoid 108, wire 107, and starting pin 106 which is engaged by the contact tongue 152. Upon the completion of this circuit the solenoid 108 is energized whereby the solenoid core is moved in the direction to move the switch element 115 to open position with respect to the terminal contacts 110 and 114, and simultaneously effecting the closing of the switches 62 and 112, whereby the electrical automatic controlling elements are placed in operable condition, the same as if the switch knob 185 had been turned manually to the "on" position.

Should it be desired to automatically place the automatic controlling means in inoperable condition, it is only necessary to insert the stopping pin 105 in the socket tube 74 at the place on the annular dial 70 coordinated with the place on the clock dial proper 69 indicative of the time at which it is desired to automatically stop the operation of the receiving apparatus.

Thus, when the inserted pin 105 is engaged by the tongue portion 152 of the contact member on the rotating arm 148, the circuit is completed through the clock mechanism and housing 67 and the hereinbefore mentioned connections between the supporting bracket and the wire 117, which latter is connected to the switch terminal contacts 111 and 100, at the time connected by the switch element 112, thence through the wires 99 and 101, solenoid coil 102 and wire 103 to the stop pin 105 which is engaged by the contact tongue 152. Upon the completion of this circuit the solenoid coil 102 is energized and the reciprocating core member carrying the switch elements 62 and 112 is moved in a direction to disconnect the switch elements 62 and 112 from the contacts 59, 60, and 100, 111, and simultaneously therewith the switch 115 is moved to connect the terminal contacts 110 and 114, at which time the knob 185 is moved automatically to the "off" position. The breaking of the connection between the contacts 100 and 111 opens the circuit through the secondary coil 119 of the transformer 120 and at the same time the breaking of the connection between the switch terminal contacts 59 and 60 opens the circuit between the chassis 56 of the radio receiver and the plugging-in socket 38 from the source of electrical energy.

In the course of its continued travel, the rotating arm 148, every time its contact tongue portion 151 engages a tubular socket member 74, unless the correlated disc element 76 happens to be set at the time in a position where its insulated insert or dead spot 91 is engaged by the cooperating tongue member 76, and provided, of course, the switch element 112 is in closing relation to the terminal contacts 100 and 111, a circuit is closed through the clock mechanism and housing 61, bracket member 123, connecting member 122, wire 121, secondary coil 119 of the transformer 120, wires 118 and 117, switch element 112 and terminal contacts 100 and 111, wires 99, 98, switch 96, wire 94, solenoid coil 93, wire 92, metal lining plate 85, the correlated disc member 79 and brush element 76, and their wire 75, and said tubular socket member 74 with which the spring tongue contact member 151 is in contact.

Upon the completion of this circuit the solenoid coil 93 is energized, thereby moving the core thereof in the direction to operate the switch 135 so as to close the motor circuit, said circuit being through the connected terminal contacts 133, 134, wire 130, connected terminal members 52 and 47 of the junction block 49, wire 45, plugging-in socket 38 from the source of electrical supply, wire 46 from said socket 38, the connected terminal members 48 and 53 of said junction block 49, wire 127, the motor 131, and wire 132 back to the switch terminal 133. Upon the completion of this circuit the motor operates, and through the link connection between the rotating crank arm 167 driven thereby and the oscillatory crank arm 161 which is clutched to the shaft 80 by the clutch member 153, said shaft 80 is rotated and, of course, the several disc elements 79 are rotated therewith. The motor continues to operate as long as the contact tongue portion 151 of the rotary element 148 is in contact with a tubular socket member 74, whose correlated disc member 79 is still in electrically conductive contact with the companion brush element 76. That is to say, the motor continues to operate until the brush element 76 is engaged with the insulated insert or dead spot 91 of the disc element; and the electrical circuit is broken upon either the up-stroke or downstroke of the oscillatory crank arm 161. It may be here, therefore, noted that unless a disc setting has been effected for the reception of a broadcast at a given time, at which time the disc will be in position where its insulated insert or dead spot 91 is engaged by its cooperative brush element 76, the motor 131, by the sequential engagement of the contact tongue portion 151 of the rotating member 148 with the tubular socket members 74, will operate intermittently at the end of each fifteen-minute period, and by the same token the motor will start operating immediately after the reception of each fifteen-minute broadcast, unless at the beginning of the next fifteen-minute period the disc element 79 has been set for the reception of a broadcast, it being understood, of course, that the dial wheel 26 has been accordingly set with relation to the disc element 79 for the selection of the station.

It is preferable to provide the hereinbefore described switch 96 in the motor circuit in order to manually close and open the circuit at will, both as a measure of safety by having the switch open when the receiving apparatus is not in use, and in an emergency necessitating the stopping of the motor before it has completed its normal operation under the automatic control. This switch may be of any approved kind, but, as

shown in the illustrated mechanical structure (see Figs. 1, 2, 3, and 5), is of the push-and-pull type with a manipulating knob 96a located conveniently on the outer side of the front wall or panel 21 of the cabinet.

The apparatus, as illustrated, is provided with the usual pilot light for illuminating the station indicating dial wheel 26, as shown conventionally at 195 in Figs. 3, 4, and 13, said pilot light being connected in an obvious manner to the regular radio receiver circuit through the wires 196 and 197, and of itself forming no part of the present invention, but only functioning in the usual way in illuminating the dial wheel 26 to facilitate the reading of the station indicating symbols thereon.

By the application of the present invention to a radio receiver a great many different stations may be selected in advance to be tuned in automatically at any desired time during the day or night, either a different station at the end of each period or the same station may be held tuned in throughout several successive periods. That is to say, in the particular adaptation illustrated in the accompanying drawings, where-in the provision for automatic reception is for periods of fifteen minutes duration each, the settings may be made for a total of twelve hours, permitting tuning in of forty-eight different stations during that time at fifteen minutes duration each, or a less number of the same duration each, as may be desired. So, too, adjustment of adjoining disc members 79 may be made to continue the reception of the broadcast from a selected station for the duration of as many fifteen-minute periods in succession as may be desired. Also, if it is desired at any time to receive the broadcast continuously from a single station, through an indefinite period, the automatic control may be cut out by disconnecting the clutch member 153 from the oscillatory crank arm 161 and with the switches 35, 62, and 112 turned on, the station can be tuned in, as desired, by manual manipulation of the toothed wheel 23 in the working adjustment of the dial 26 and the connected rotors 29 of the condensers 31 and 32.

Then, again, if it is desired to set the automatic controlling means for tuning in at a later time, the clutch 153 is engaged with the crank arm 161, and with the switch 35 on, and the switches 62 and 112 off, the starting pin 106 is inserted in the proper socket tube 74 for the time of starting operation for automatic tuning in; and if it is desired to automatically place the apparatus in inoperative condition the stopping pin 105 is accordingly inserted in the proper socket tube 74.

An example of a disc setting is illustrated in Figs. 8, 9, 10, and 11, wherein the discs 79 for the 5 o'clock and 8:45 o'clock periods have been set, and, as shown in Fig. 8, the key or setting pin 186 has been inserted in locking engagement with the disc 79 for the 6 o'clock period. After the key or setting pin 186 is withdrawn from engagement with the last mentioned disc 79, the three mentioned discs will rotate in their relatively set relation on the shaft 80, and when the disc for the 5 o'clock period has been brought into electrically conductive contact with its companion brush element 76, thereby completing the circuit through the electric motor 131, the shaft 80 is rotated and continues to rotate until the insulated insert or dead spot 91 on the disc is

brought into engagement with the brush element 76, thereby breaking the circuit and stopping rotation of the shaft.

At the end of the fifteen-minute period during which the shaft has remained idle and the broadcast has been received from the station for which the dial wheel 26 had previously been set in relation to the 5 o'clock disc, the contact tongue 151 of the rotary clock element 148 will 10 have engaged the tubular socket member 74 for the 5:15 o'clock period, whereupon the motor circuit will be closed through the electrical conductive contact between the correlated disc element 79 and brush element 76, and the shaft 15 80 is accordingly rotated until the insulated insert or dead spot 91 of that particular disc is in contact with the companion brush element, thereby breaking the circuit so that the shaft remains again idle through another fifteen-minute 20 period, during which time the broadcast from the same or a different station may be received according to the relative setting of the dial wheel 26, and so on until the controlling apparatus has been rendered inoperative either by manual manipulation of the switches 35, 62, and 112, or 25 automatically, at a predetermined time, by the insertion of the stopping pin 105 in the proper tubular socket member 74, as has been herein-before set forth.

By the correlated views in Figs. 9, 10, and 11, the relative location of the insulated inserts or dead spots 91 of the 5 o'clock and 8:45 o'clock discs 79 are on opposite sides of the dead central horizontal line in which the insulated insert or dead spot 91 of the 6 o'clock disc is located. This is to show that such relative location will occur, variably, in the adjustment of the several disc elements 79 throughout the entire series thereof on the shaft 80, and no matter 35 on which side of the dead central line the spot 91 may be positioned at the time the electrical circuit is closed through any disc 79, it will be brought into dead central position for engagement with its correlated brush element 76 on 40 either the upstroke or downstroke of the crank arm 161, as previously herein stated, and whereupon the shaft 80 remains stationary until the circuit is closed through the next adjoining disc element 79.

Obviously the operating and controlling means of the present invention may be applied to different makes of radio receiving apparatus without material alteration in either, and at the same time the construction and arrangement of the 55 several parts and the particular application thereof may be modified in many respects without in the least departing from the spirit and scope of the invention as defined by the appended claims. The invention, therefore, is not limited to the specific details of structure shown in the accompanying drawings.

Having thus described my invention, what I claim as new and desire to secure by Letters 60 Patent is:

1. The combination of a radio receiver having a manually operable rotatable tuning element, a relatively movable station indicator dial, and automatic time controlled tuning-in means including a shaft geared to said manually operable rotatable tuning element, a series of disc elements 70 rotatably mounted on said shaft and frictionally held with respect to each other and to said shaft whereby to rotate together but permitting independent rotation of the shaft and the other disc 75

elements when one of said disc elements is held against rotation, said disc elements being respectively coordinated sequentially with equally divided intervals of time, means for releasably holding said disc elements selectively, at will, while manually turning said shaft and said gear connected rotatable tuning element to set the station indicating dial with respect to said disc element so held, and time controlled power means releasably connectible with the shaft carrying 10 said disc elements and including a controlling clock mechanism and switch elements in electrical circuits in which said disc elements are respectively included, whereby, at a given time and throughout the duration of the interval for 15 which a disc element is selectively set, the radio receiver is operated automatically.

2. The combination of a radio receiver having a manually operable rotatable tuning element, a relatively movable station indicator dial, and automatic time controlled tuning-in means including a shaft geared to said manually operable rotatable tuning element, a series of disc elements 20 rotatably mounted on said shaft and frictionally held with respect to each other and to said shaft whereby to rotate together but permitting independent rotation of the shaft and the other disc elements when one of said disc elements is held against rotation, said disc elements being of electrical conductivity and provided with an insulated portion and respectively coordinated sequentially with equally divided intervals of time, a separate electrically conductive brush element cooperating with each of said 25 disc elements, a clock mechanism having a series of separate stationary contact elements insulated from each other in spaced relation and coordinated one each to the respective disc elements and in the same interval of time relation to each other, said stationary contact elements being 30 electrically connected with said brush elements, a movable element successively engageable with said stationary contact elements and included in a switch operating circuit which is closed when said movable element is in engagement with one 35 of said stationary contact elements and the coordinated disc element thereof is in contact with its cooperative companion brush element at any place except said insulated portion, and an electric motor releasably connectible, at will, to the 40 shaft carrying said disc elements, the herein described switch controlled by said clock mechanism and disc elements controlling the operation of said motor and being normally open.

3. The combination of a radio receiver having a manually operable rotatable tuning element, a relatively movable station indicator dial, and automatic time controlled tuning-in means including a shaft geared to said manually operable rotatable tuning element, a series of disc elements 45 rotatably mounted on said shaft and frictionally held with respect to each other and to said shaft whereby to rotate together but permitting independent rotation of the shaft and the other disc elements when one of said disc elements is held against rotation, said disc elements being of electrical conductivity and provided with an insulated portion and respectively coordinated sequentially with equally divided intervals of time, 50 a separate electrically conductive brush element cooperating with each of said disc elements, a clock mechanism having a series of separate stationary contact elements insulated from each other in spaced relation and coordinated one each 55

to the respective disc elements and in the same interval of time relation to each other, said stationary contact elements being electrically connected with said brush elements, a movable element successively engageable with said stationary contact elements and included in a switch operating circuit which is closed when said movable element is in engagement with one of said stationary contact elements and the coordinated disc element thereof is in contact with its cooperative companion brush element at any place except said insulated portion, an electric motor releasably connectible, at will, to the shaft carrying said disc elements, the herein described switch controlled by said clock mechanism and disc elements controlling the operation of said motor and being normally open, and a combined manually and electrically operable switch in said motor switch controlling circuit.

4. The combination of a radio receiver having a manually operable rotatable tuning element, a relatively movable station indicator dial, and automatic time controlled tuning-in means including a shaft geared to said manually operable rotatable tuning element, a series of disc elements rotatably mounted on said shaft and frictionally held with respect to each other and to said shaft whereby to rotate together but permitting independent rotation of the shaft and the other disc elements when one of said disc elements is held against rotation, said disc elements being of electrical conductivity and provided with an insulated portion and respectively coordinated sequentially with equally divided intervals of time, a separate electrically conductive brush element cooperating with each of said disc elements, a clock mechanism having a series of separate stationary contact elements insulated from each other in spaced relation and coordinated one each to the respective disc elements and in the same interval of time relation to each other, said stationary contact elements being electrically connected with said brush elements, a movable element successively engageable with said stationary contact elements and included in a switch operating circuit which is closed when said movable element is in engagement with one of said stationary contact elements and the coordinated disc element thereof is in contact with its cooperative companion brush element at any place except said insulated portion, an electric motor releasably connectible, at will, to the shaft carrying said disc elements, the herein described switch controlled by said clock mechanism and disc elements controlling the operation of said motor and being normally open, and a supplemental switch in said motor switch controlling circuit, said supplemental switch being manually operable and having electrical means cooperable with said clock control mechanism for opening and closing the switch automatically at predetermined times.

5. Means for tuning-in radio receiving apparatus, comprising a shaft operably connected to a manually operable tuning in instrumentality of the apparatus, a series of like disc elements mounted on said shaft and frictionally engaged whereby to normally rotate together with the shaft, said discs being of electrical conductivity provided with an insulated portion, a separate brush element of electrical conductivity in cooperative contact with each of said disc elements, a clock mechanism having a rotatable element provided with a contact portion and included in an electrical switch controlling circuit in which said

disc elements are also electrically connected, an annular series of stationary contact members corresponding in number to said disc elements and respectively coordinated one each to one of said disc elements, each stationary contact member being electrically connected to the companion brush element of its coordinated disc element, whereby said electrical switch controlling circuit is intermittently closed as the contact portion of said rotary element of the clock mechanism successively engages said stationary contact members, a motor controlled by said switch, and power means operated by said motor and releasably connectible with the shaft carrying said disc elements, at will.

6. Means for tuning-in radio receiving apparatus, comprising a shaft operably connected to a manually operable tuning in instrumentality of the apparatus, a series of like disc elements loosely mounted on said shaft and frictionally engaged whereby to normally rotate together with the shaft, said discs being of electrical conductivity and each being provided with an insulated portion, a separate brush element of electrical conductivity in cooperative contact with each of said disc elements, said brush elements being included in a circuit including a controlling clock mechanism, means for selectively engaging and holding said disc elements from rotation whereby to set the manually operable tuning-in instrumentality relative to the disc so engaged and held, a supplemental electrical switch in the controlling circuit, electrical means for automatically closing said supplemental switch including a circuit terminal element insertable selectively in correlation to the stationary contact member of the clock mechanism coordinated with the disc element for the desired time of starting radio reception, and similar means for opening said supplemental switch at a predetermined time for cessation of radio reception.

7. The herein described tuning-in means for radio receiving apparatus, comprising a shaft operably connected to a manually operable tuning-in instrumentality including a station indicating dial, a series of frictionally engaged like disc elements loosely mounted whereby to normally rotate together with the shaft, said disc elements being of electrical conductivity and each being provided with an insulated portion, said disc elements being coordinated for like intervals of radio reception but beginning at sequentially different times, means for releasably holding said disc elements selectively, at will, while rotating said shaft together with the manually operable tuning in instrumentality whereby to set the station indicating dial and the tuning-in instrumentality relative to the disc elements so held, the insulated portions on said disc elements being located in a common horizontal plane when the elements are releasably held as and for the purpose described, and time controlled means for automatically moving said disc elements to the same position in which they are releasably held for the aforesaid manual station selecting manipulation, said means including a motor releasably connectible to said shaft, a normally open circuit controlling switch for the motor, and an electrical controlling device for closing said switch, the circuit for which includes a direct electrical connection between the device and said disc elements, separate brush elements of electrical conductivity in cooperative contact with each of said disc elements, said brush elements being separately connected to stationary contact members which are

- spaced apart corresponding to the intervals of time for which the disc elements are coordinated, and a movable contact member in a clock mechanism successively engaging said stationary contact members whereby to complete the circuit for the energization of the electrical closing device for the motor controlling switch, and whereby the motor continues to operate until the companion brush element is engaged by the non-electrical surface spot of the disc element, thereby breaking the motor controlling circuit.
8. Means for the automatic tuning-in of radio receiving apparatus, comprising a shaft operably connected to a manually operable tuning-in instrumentality, said instrumentality including a visible station indicating dial, a motor releasably connectible with said shaft, at will, a series of frictionally engaged disc elements loosely mounted whereby to normally rotate together with the shaft, means for selectively engaging and holding said discs while the shaft is rotated independently thereof whereby to adjustably position the station indicating dial and manually operable tuning-in instrumentality relative to the disc elements so held, and time controlled means for operating said motor including a normally open switch and an electrical device for automatically closing the switch, the circuit for said electrical switch closing device including therein said disc elements, and a series of correlated brush elements engaging said disc elements and separately connected to a series of stationary contact elements spaced apart and individually coordinated with the respective disc elements, and a movable contact element in a clock mechanism engageable sequentially with said stationary contact members.
9. Means for the automatic tuning-in of radio receiving apparatus, comprising a shaft operably connected to a manually operable tuning-in instrumentality, said instrumentality including a visible station indicating dial, a motor releasably connectible with said shaft, at will, a series of frictionally engaged disc elements loosely mounted whereby to normally rotate together with the shaft, means for selectively engaging and holding said discs while the shaft is rotated independently thereof whereby to adjustably position the station indicating dial and manually operable tuning-in instrumentality relative to the disc elements so held, and time controlled means for operating said motor including a normally open switch and an electrical device for automatically closing the switch, the circuit for said electrical switch closing device including therein said disc elements, a series of correlated brush elements engaging said disc elements and separately connected to a series of stationary contact elements spaced apart and individually coordinated with the respective disc elements, a movable contact element in a clock mechanism engageable sequentially with said stationary contact members, and a normally closed switch in the reproducer circuit of the radio receiving apparatus, said last mentioned switch being operably connected to the electrical closing device for the motor controlling switch whereby to be opened upon the closing of said motor controlling switch.
10. The combination of a radio receiver, combined manually operable and automatically operable tuning-in means, the automatic operating means including an electric motor releasably connectible therein, a normally open switch in the motor controlling circuit, an electrical device for closing said switch, a clock mechanism in-
- cluding circuit controlling elements cooperating with correlated, sequentially timed, movable station selecting elements operated and controlled by said motor, and controlling said electrical switch closing device, a normally closed switch in the reproducer circuit of the radio receiver operably connected to said electrical switch closing device whereby to be opened when said device is operated to close said normally open motor circuit controlling switch, a manually operable switch for opening and closing the energizing circuit of the radio receiver, a supplemental combined manually operable and automatically operable switch for the energizing circuit of the receiver, electrical means for closing said supplemental switch including a circuit terminal element insertable selectively for engagement by a circuit controlling element of the clock mechanism, and similar electrical means for automatically opening said supplemental switch at a pre-determined time.
11. The herein described tuning-in means for radio receivers, comprising a series of like frictionally engaged disc elements mounted on a shaft to normally rotate in unison therewith, said shaft being operably connected to a manually operable tuning-in instrumentality of the radio receiver, means for releasably holding said disc elements, selectively at will, while adjusting said manually operable tuning-in instrumentality in relation to the discs so held for reception of the broadcast from a desired station at a given time, releasably connectible motor operated means for rotating said shaft and the disc elements thereon, and time controlled means for the actuation of said motor operating means, said controlling means including a clock mechanism, having a rotating element traveling coincidentally with the hour hand spindle of the clock mechanism and provided with a contact portion, and a concentric annular series of spaced stationary contact members sequentially engageable by the contact portion of said rotatable element of the clock mechanism, each of said stationary contact members being individually connected electrically with a separate brush element cooperatively engaging one of said disc elements, said disc elements being of electrical conductivity but having an insulated portion whereby, upon engagement of the cooperating brush element with said portion, an electrical circuit is thereby broken and the motor operated means rendered inactive.
12. The herein described automatic controlling and operating means for tuning-in radio receivers, comprising a series of individually adjustable, progressively timed, coordinated disc elements cooperatively associated for selective setting and adjustment with respect to a manually operable tuning-in instrumentality of the radio receiver, and cooperating time controlled means including a clock mechanism having a rotatable element provided with a contact portion, said element being included in the electrical controlling circuit for releasably connectible motor operated means for the joint actuation of said disc elements, and a concentric annular series of correspondingly timed coordinated stationary contact members each of which is individually electrically connected to a separate brush element, each of which latter cooperatively engages one of said disc elements, said disc elements being of electrical conductivity and incorporated in the circuit of said connectible motor operated actuating means, but having a surface portion of non-electrical conductivity whereby, upon engagement of the coop-

erating brush element with said portion, said electrical circuit is broken and the motor operated actuating means rendered inactive.

13. In automatic tuning-means for radio receivers, an electrical controlling circuit including an annular series of spaced tubular socket members, each individually electrically conductive, a rotatable electrical terminal element having a contact portion engageable successively with said socket members during its rotation, a station selecting unit comprising separate electrically conductive rotatable disc elements collectively electrically connected in said circuit and each having an electrical non-conductive surface portion, individual brush elements in contact with said disc elements and separately connected respectively to one of said socket members in coordinated timed relation to the rotatable disc element with which the connected brush element cooperates, said controlling circuit being alternately closed and opened during the rotation of said rotatable terminal element which sequentially engages said tubular members and also during the rotative movement of said rotatable disc elements, said circuit controlling the motive means for said disc elements, an automatically operable switch for opening and closing the receiver energizing circuit, an electrical device for moving said switch to closed position including a circuit, one terminal of which is said rotatable terminal element, and the other terminal of which is a pin insertable selectively in one of said tubular socket members and into the path of said rotatable terminal element to be thereby engaged, and an electrical device for moving said last named switch to open position, the controlling circuit of which includes said rotatable terminal element and a corresponding terminal pin insertable selectively in said tubular socket members.
14. Time controlled automatic tuning-in means for radio receivers, comprising, in combination with an ordinary radio receiving apparatus having a manually operable tuning-in instrumentality and a cooperating automatically operable time coordinated station selecting instrumentality, a supporting panel having a circular opening, a clock, the dial of which is inserted in and visible through said panel opening, and the mechanism of which is contained within a housing supported 50 in spaced relation to the inner face of said panel, a rotatable circuit terminal element located between the panel and the clock housing and mov-

able coincidently with the hour hand spindle of the clock, said rotatable terminal element being incorporated as a part of the operating circuit for the automatically operable tuning-in instrumentality, and also incorporated as a part of two additional circuits, one for controlling the selectively timed automatic starting and the other likewise the stopping of effective conditioning of said operating circuit, an annular series of spaced open-ended tubular stationary circuit terminal 10 contact members extended through said supporting panel in concentric relation to the clock dial, said tubular members being respectively correlated to the hour and fractional time markings of the clock dial and being incorporated with individual connections in said operating circuit for the tuning-in instrumentality, a circuit terminal pin insertable selectively in one of said tubular contact members but electrically insulated therefrom and projecting beyond the inner end thereof, 20 said terminal pin being incorporated in said starting circuit, and a like terminal pin incorporated in said stopping circuit, said rotatable terminal element having a brush contact portion engageable in its rotation successively with said tubular 25 contact members and with the inserted terminal pins.

15. In an automatic tuning-in instrumentality for radio receivers, a tuning-in controlling circuit, an automatic starting circuit, an automatic stopping circuit, a clock mechanism having a movable terminal element rotatable coincidently with the hour hand of the clock mechanism, and incorporated as a part of each of said operating, starting, and stopping circuits, an annular series of 30 open-ended tubular stationary terminal members separated and insulated from each other and being incorporated with individual connections in said operating circuit, said stationary terminal members being respectively correlated to the hour and fractional time markings of the dial of said 35 clock mechanism, and separate terminal pins incorporated respectively as a part of said starting and stopping circuits and being respectively insertable selectively in one of said tubular stationary terminal members but insulated therefrom and projecting beyond the inner end thereof, said movable terminal element of the clock mechanism in its rotation successively engaging said stationary tubular contact members and the inserted terminal pins. 40 45 50
